UNITED STATES PATENT OFFICE.

HYMAN CHARM, OF DORCHESTER, MASSACHUSETTS.

CONTAINER FOR ELECTRIC WIRES.

1,421,168.

Specification of Letters Patent. Patented June 27, 1922.

Application filed April 5, 1920. Serial No. 372,091.

To all whom it may concern:

Be it known that I, HYMAN CHARM, a citizen of the United States of America, and a resident of Dorchester, in the county 5 of Suffolk and State of Massachusetts, have invented certain new and useful Improvements in Containers for Electric Wires, of which the following is a specification.

This invention relates to wire-containing 10 strips adapted to be used in wiring buildings and has for its object the provision of a device of this character which may be assembled readily and in which the various compartments are each of a size to receive 15 a single insulated wire such as is in general use in wiring buildings.

A further object of the invention is to provide a containing strip which will be ornamental when installed and in which the 20 usual coverplate is dispensed with.

The invention consists primarily of a two-part container the body part having two parallel compartments each adapted to receive a single wire while the other part is 25 adapted to be frictionally retained between the portions of the body part in which said compartments are located.

The invention further consists of long 30 strips of sheet metal having their opposite edges bent over to form two parallel but separated cylindrical portions each having a bore, the diameter of which substantially corresponds to the diameter of the insulated wire to be contained therein.

35 The invention further consists in providing such strip with another wire containing member formed of spring metal, U-shaped in cross section and having its opposite edges flaring outwardly and adapted 40 when positioned between said cylindrical portions to be locked beneath said cylindrical portions thereby preventing the accidental displacement thereof.

The invention further consists in certain 45 novel features of construction and arrangement of parts which will be understood by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the 55 invention consists can be variously arranged

and organized and the invention is not limited to the precise arrangement and organization of these instrumentalities as herein shown and described, except as required by the scope of the appended claims. 60

Of the drawings:

Figure 1 represents a plan of one part of the container.

Figure 2 represents a plan of the other part of the container. 65

Figure 3 represents a plan of the complete container.

Figure 4 represents a transverse section on line 4, 4, on Fig. 3, drawn to an enlarged scale. 70

Figure 5 represents an end view of the central part of the container, drawn to an enlarged scale.

Figure 6 represents a plan of the container showing the central part being slipped 75 into the body part, and

Figure 7 represents a side elevation of the container showing the central portion being snapped into position on the body part. 80

Similar characters indicate like parts throughout the several figures of the drawings.

In the drawings, 10 represents a back plate having a plurality of counter-sunk 85 perforations 11 therein to receive screws for securing the plate to the wall of a building.

The opposite edges of said plate are bent over toward each other to form parallel 90 cylindrical portions 12 each to receive an insulated wire 13, each cylindrical portion having an inner diameter corresponding to the diameter of the wire to be installed.

The cylindrical portions 12 are separated 95 sufficiently to receive another wire-containing member 14 in which is positioned an electric wire 15.

The opposite edges of the member 14 are flared outwardly as indicated at 16 in Figs. 100 4 and 5 of the drawings.

The member 14 is made of spring metal and when in position on the back plate 10 and between the cylindrical portions 12 thereof, the flaring edges 16 will extend beneath the cylindrical portions 12 thereby preventing the accidental displacement of said member 14. 105

The interior diameter of the cylindrical portions 12 and the member 14 is substan- 110

tially the diameter of the usual insulated electric wire used in the construction of buildings.

In some cases where only two wires are necessary for the installation, the detachable member 14 may be omitted but it is preferable that this member 14 should be inserted between the cylindrical portions 12 even if it contained no wire.

10 It is obvious that a strip thus constructed is more or less ornamental in appearance which is of some advantage where the strips are necessarily exposed to view.

One of the great difficulties to be found 15 in strips now in general use, is that they are provided with covers which do not always fit the body portion and require more or less hammering in order to properly position them upon said body portion.

20 This hammering is liable to break and injure the plaster or other surface to which the body portion of the strip is secured.

With the strip constructed in accordance 25 with the present invention, there is no necessity of hammering as the back plate is secured to the wall by means of screws and the device may be completed by sliding the intermediate member 14 into position as indicated in Fig. 6 or by snapping it into 30 position as indicated in Fig. 7.

The flaring edges 16 yield sufficiently in the last case to permit them to pass the widest part of the cylindrical portions 12, subsequent to which they will spring outwardly and engage the under surface of the 35 said cylindrical portions as indicated in Fig. 4 of the drawings.

When thus positioned the detachable strip 40 may be quickly removed when desired but it cannot be accidentally displaced.

In practice these strips are made several feet in length with their ends abutting other similar strips when installed.

It is believed that the operation and many advantages of the invention will be understood without further description.

Having thus described my invention, I claim—

1. A containing strip for electric wires consisting of a back plate having parallel separated cylindrical wire-enclosing portions having their walls extending to the face of said back plate and a detachable wire-enclosing member having resilient edges to engage said cylindrical wire-enclosing portions.

2. A containing strip for electric wires consisting of a back plate having parallel separated cylindrical portions adapted to receive electric wires and a detachable wire-enclosing member adapted to be positioned between said cylindrical portions and having outwardly flaring edges adapted to extend beneath said cylindrical portions.

3. A containing strip for electric wires provided with two separated parallel wire-enclosing portions and a detachable wire-enclosing member between said separated wire-enclosing portions and with its edges in frictional engagement with said wire-enclosing portions.

4. A containing strip for electric wires provided with two separated parallel wire-enclosing portions and a detachable wire-enclosing member of spring metal, the edges 75 of said detachable wire-enclosing member being separated normally a greater distance than the width of the space between said separated parallel portions.

Signed by me at 746-7 Old South Bldg., 80 Boston, Mass., this 3rd day of April, 1920.

HYMAN CHARM.
